UNITED STATES PATENT OFFICE.

JOHN E. WOOD, OF PITTSFIELD, MASSACHUSETTS.

EAR-PHONE ATTACHMENT.

Application filed January 23, 1925. Serial No. 4,286.

To all whom it may concern:

Be it known that I, JOHN E. Wood, a citizen of the United States, residing at Pittsfield, in the county of Berkshire and State of Massachusetts, have invented certain new and useful Improvements in Ear-phone Attachments, of which the following is a specification.

This invention relates to ear-phone attachments and is particularly adapted for radio uses.

The primary object of my invention is to provide a light, simple, compact, quick detachable attachment for the conventional ear-phones now commonly used in radio for the purpose of excluding to a certain extent, if desired, external sounds.

A further object of my invention is to provide a compressible cushion around the outside of the periphery of the attachment which contacts with the head of the user to thereby prevent the so-called "radio rash" occasioned by the use of the ordinary ear-phone.

Still another feature of the invention resides in the fact that the attachment is so constructed that the compressible cushion aforesaid is situated in such a manner as to completely surround the ear of the user to thereby prevent the ingress of foreign noises.

Still another and important feature of the invention is the fact that the ear-phone attachment contemplated by my invention spaces the ear-phone diaphragm from the ear of the user a considerable distance to avoid the disagreeable and harmful results on the ear of the user, due to static conditions of the air or the condition of the phone.

In the accompanying drawing:

Fig. 1 is a view in front elevation of my attachment.

Fig. 2 is a view in rear elevation of the same, and

Fig. 3 is a view, partly in section, of my invention attached to an ordinary ear-phone.

Referring now more particularly to the drawing, wherein like reference characters represent like parts, 1 designates the ear-phone attachment generally, which is made of any suitable material, but preferably aluminum because of its lightness, 2 designates an annular outstanding collar adapt-

ed to contact with the ear-phone when in use, 3 is the resilient fingers which are adapted to snap onto the ear-phone, 4 is an integral flange, and 5 is an oppositely disposed horizontal annular flange. It will be noted that by reason of the peculiar Z-shaped formation of the device that a pocket 6 is formed along the outside of the attachment for the purpose of receiving the annular felt washer 7. This felt washer is cemented within the pocket of the attachment, but may be withdrawn when desired for replacement. The collar 2 provides a ready means of attachment of the resilient fastening clips aforesaid and in addition serves the function of abutment against the ear-phone. The circumferential horizontally extending flange 5 effectually forms the pocket for the washer and furthermore limits the outward movement of the washer.

It will be apparent to those skilled in the art that by virtue of the peculiar formation disclosed in the drawing, of my application that an extremely simple construction is provided which serves the functions of spacing the ear from the diaphragm, providing a soft resilient contact with the head of the user and of surrounding the entire ear of the user when in use for the purpose of preventing annoyance by conversation of others in the place of use. However, the attachment does not necessarily exclude external sounds, such as conversation directed at the user. It will be obvious that my attachment provides an insulation between the receiver and the skull of the head, and those harsh sounds due to the static conditions or tuning in of other receivers are much less annoying although the actual program being listened to is loud and clear.

Having thus described my invention, what I claim is:

1. An ear-phone attachment, comprising a body portion having integral oppositely disposed circular flanges of substantially Z-shaped formation, spring clips secured to one of said flanges for attachment to the ear-phone, said ear-phone attachment being provided with a soft bearing surface for contact with the head of the user and adapted to entirely surround the ear of the user, substantially as described.

2. An ear-phone attachment, comprising a body portion having an integral circum-

2
ferential flange extending at substantial right angles to the body portion, spring devices attached to said flange for detachable connection with the ear-phone, a circular resilient washer secured to said body portion, said washer being of greater internal circumference than the body portion and the

said flange, whereby an enlarged yielding contact surface is provided for surrounding the ear of the user, substantially as described.

In testimony whereof I affix my signature.

JOHN E. WOOD.
